United States Patent Office

Des. 206,840
Patented Jan. 31, 1967

206,840

TELLER'S COUNTER

Robert L. Ziegelman, Farmington, Mich., and Norman H. Ziegelman, Southfield, Mich. (both of 167 Townsend, Birmingham, Mich. 48011)

Filed Feb. 28, 1966, Ser. No. 1,201

Term of patent 14 years

(Cl. D80—2)

FIG. 1

FIG. 2

FIG. 3

FIG. 1 is a perspective view of a teller's counter, showing our new design;

FIG. 2 is an elevational view taken from one end thereof, the opposite end being a mirror image of the end shown; and

FIG. 3 is a top plan view thereof.

I claim:

The ornamental design for a teller's counter, as shown and described.
